UNITED STATES PATENT OFFICE.

ALFRED LETORT AND LOUIS CHAMBON, OF PARIS, FRANCE.

MACHINE FOR BREAKING BLOCKS OF SUGAR INTO PIECES AND PLACING THEM IN BOXES.

Application filed September 13, 1921. Serial No. 500,371.

To all whom it may concern:

Be it known that we, ALFRED LETORT and LOUIS CHAMBON, citizens of the Republic of France, residing at Paris, France, have invented Improvements in Machines for Breaking Blocks of Sugar into Pieces and Placing Them in Boxes, of which the following is a specification.

The present invention has for its object 10 a machine for breaking into pieces blocks of sugar and placing them in boxes.

To facilitate the understanding of the description of the machine in question, the accompanying drawing is given by way of example, in which:

Fig. 1 is a side elevation of the part of a machine of the above kind to which the invention more particularly relates.

Fig. 2 is a transverse elevational section 20 on the line II, II in Fig. 1.

Fig. 3 is a longitudinal elevational section of the extreme right hand portion of the machine.

Fig. 4 is a plan view of a device for folding the paper for making the boxes during a filling operation.

Fig. 5 is a plan view corresponding to Fig. 3, and indicating the means employed for removing completed and filled boxes.

Fig. 6 is a side elevation of the device for distributing the blocks of sugar in the machine, the device being so disposed that its axial plane is perpendicular to the plane of Fig. 1 and passes through the line VI, VI, in that figure.

Fig. 7 is a plan view of parts in Fig. 6, and indicates the means employed for effecting on the one hand the distribution to the machine of the unbroken lumps, and on the other hand the removal of the completed and filled boxes.

Fig. 8 is a section of the device for transferring the blocks to the conveyor which takes them to the appliance for placing them in the boxes.

The machine of the present invention operates automatically and comprises feeding means which operates automatically to transfer the blocks three at a time from the front of a first conveyor, upon which said blocks have been placed by hand one behind the other, to a second conveyor which is given an intermittent movement and which conveys the blocks to a breaking de-

vice and finally under a plunger plate which 55 forces them into a boxing frame, the forming of the boxes being accomplished in a known manner by mechanism which forms no part of the present invention.

The various parts of this machine are operated by a synchronous intermittent motion, and in order to ensure absolute synchronism, control of the principal conveyor, of the crushing mechanism and of the packaging means, is effected by a single mechanism.

The improved machine comprises, as shown in Figs. 6, 7 and 8, a conveyor comprising an endless band 1 which passes over two drums 2 and 3 mounted respectively on shafts 2 and 3.

The blocks of sugar 7 are placed by hand on the conveyor one behind the other. The conveyor is arranged in such a way that its central vertical longitudinal plane C, D, 75 Fig. 7, is perpendicular to the plane of Fig. 1 and passes through the line VI, VI shown in that figure. The end of the conveyor where the blocks are placed on it near drum 2 is situated in rear of the plane of Fig. 1. 80

The conveyor has an intermittent movement which is communicated to it by means of the slotted wheel 4 operated by the pin or roller 5.

The intermittent movement of the conveyor is effected by shaft 34, which controls all the elements of the machine, in a manner such as to strictly synchronize the crushing means, and particularly the principal conveyor.

The slots 4' on the wheel 4 being disposed in a manner to have the following effect:

The blocks 7, at the end of their advance by the conveyor in the direction of the arrow a, pass on to an elevator 6 adapted to transfer them to a second conveyor which is indicated by the single broken line 7 in Fig. 8, and will be described later. In order that the elevating movement of the blocks may be effected regularly it is necessary that the conveyor 1 should receive at the moment of this elevation a slight rearward movement. It is for this purpose that the slots 4' on the wheel 4 should be specially formed as, for example, as shown in 105 the drawing.

When the blocks 7 have passed onto the elevator table 6, and subsequent to the slight

rearward movement of the conveyor 1, the table 6 receives a rising movement which is communicated to it by a rod 6' receiving its vertical movement from a cam 6''' through the intermediary of a lever 6'' (Fig. 8) and which is adapted, as stated above, to transfer the blocks to the conveyor 7. This vertical movement of the elevator plate takes place while the conveyor 7 is at rest, at which time 10 said conveyor 7 occupies the position shown in Fig. 1 and the blocks, placed upon the elevator 6, engage without difficulty between two successive driving bars of said conveyor. The conveyor (Figs. 1 and 3) comprises 15 driving bars or abutment pieces 8 whose ends are connected to lugs 9 on steel bands 10 which form an endless chain, and which pass over the drums 11 and 12 which transmit an intermittent advancing movement to 20 the conveyor, in the direction of the arrow e, this movement being produced by the slotted wheel 13 co-operating with the rollers or pins 14, 15, 16. The driving bars 8 are provided with spring pushers that permit 25 the blocks of sugar to spread after they have been subjected to a breaking operation.

The fact that the two conveyors 1 and 7, and the elevator 6, are all controlled by the same shaft and by means of a Maltese cross, 30 assures a sufficient precision in the different operations, so that the lumps, raised by elevator 6, are inserted between the bars 8, of conveyor 7.

The breaking of the blocks is effected by 35 passing the blocks between two cylinders 17, 18, the peripheries of which are provided with teeth or blades 17', 18' (Figs. 1 and 3); the projection and number of their teeth are definitely settled so as to constitute shears, 40 which break the blocks into pieces the dimensions of which depend on the number of pieces desired. The pieces are not separated one from another or disarranged by the breaking.

The crushing mechanism is also operated 45 by an intermittent movement taken from the main control shaft 34 (Fig. 6) by means of wheels 35, 36, the Maltese cross 13, the fingers 14, 15, and 16, and wheels 37 and 38. 50 Since movement of the conveyor is controlled by this same Maltese cross 13, and wheels 37 and 39, the synchronism of the movements of these two devices, is perfect.

The blocks thus broken arrive above a 55 funnel-like frame 19 into which they are pushed by the action of plate 20 operated by a plunger or pushing device 21 which receives a quick descending movement controlled by the double cam 21''' which carries 60 three notches 40, 41 and 42, of varying depths corresponding each to one of the three sizes of sugar particles to be boxed. A lever with rollers 21'' coacts with cam 21''' and communicates its movement to the pusher 21, by means of arm 21'. Cam 21'''

being mounted on the same shaft as the plate carrying the fingers 14, 15, and 16, assuring movement of the cross 13, it follows that this device operates in perfect synchronism, with the conveyor.

Prior to this, the machine has formed around the funnel 19 the paper box or carton for the reception of the sugar, the forming of the box being effected as mentioned above by means of devices described in the 70 French patent specification No. 414,652 of 1910, which devices are embodied in the machine constituting the object of the present invention with the following complementary appliances: The paper appropriately prepared, as indicated in the said cited French patent, is cut to dimensions corresponding with those of the box to be formed. The cutting is effected by means of a cutter 20' operated in any suitable way as soon as the paper, 80 held by fingers 22, has advanced for a desired distance along to the supporting table 22' under the action of the feed or supply collars 22''.

Immediately after the cutting, the fingers 90 22 are raised slightly, by means of a suitable controlling mechanism, in a manner to produce the initial folding of the sides c', c'' of the box against the walls of the funnel 19. The folding is completed by means of the 95 folders 23, 24, which are pressed by springs 23', 24' against the side walls of the funnel 19.

The blade folders 25, 26 in continuing 100 their travel bend the pasted parts p', p''. At this moment the movable bottom 27 is raised; the spring blades 28, 29, with which the bottom is provided fold the sides c'', c''' of the box against the faces of the funnel 19 while the blade folders 25, 26, are withdrawn 105 so that they do not contact with the others.

Towards the end of this movement, the plate 20 acts on a second row of blocks, then a third, after each successive advance of the 110 blocks towards the upper opening of the funnel 19.

In each case, at the moment of placing the last block of sugar in the box, the plate 20 is given a descending movement greater than 115 the preceding descending movement so as to discharge at one and the same time the finished box and the sugar which it encloses, the blocks being broken into pieces.

The finished and loaded box is then, by 120 means of a lateral pusher 30 operated by a suitable transmission mechanism 30', 30'', 30''', brought on to a conveyor consisting of an endless belt 31 which passes over drums or pulleys 31', 31'' operated in a manner to 125 have a continuous movement which translates the filled and finished boxes to the outside of the machines. The central vertical plane E, F (Fig. 7) of the conveyor is arranged to be perpendicular to the plane of 130

Fig. 1 and to pass through the line II, II in that figure.

It should be noticed that the machine constructed according to the present invention comprises pincers 32 which, before the passage of the boxes, on the endless belt 31, exert a strong pressure on the sides of the boxes to ensure effective sticking of the paste. These pinching members 32, are operated in their desired movements, by a cam 43, coacting with a wheel 46 by means of lever 44.

Having thus described the nature of the said invention and the best means we know 15 of carrying the same into practical effect, we claim:—

1. A machine for breaking lump sugar, and for placing it in successive layers, in boxes, comprising, in combination, a conveyor having endless bands, crushing rolls, and pusher mechanism for placing the sugar into boxes, and actuating mechanism for simultaneously operating the three said devices with an intermittent movement, the 25 actuating mechanism including a Maltese cross and coacting fingers.

2. A machine for breaking lump sugar, and for placing it in successive layers, in boxes, comprising, a conveyor having an 30 operating drum and mounted on a shaft, crushing rolls, and mechanism for intermittently operating the conveyor and rolls, said mechanism including a second shaft, a Maltese cross mounted on the second shaft, 35 a wheel having fingers which coact with the Maltese cross, a toothed wheel mounted on the second shaft, a roll wheel fixed to one of the rolls, and a wheel mounted on the drum shaft, the toothed wheel engaging di-

rectly with the roll wheel and the wheel on 40 the drum shaft.

3. A machine for breaking lump sugar, and for placing it in successive layers, in boxes, comprising, in combination, a conveyor, a crusher, and mechanism, including 45 a Maltese cross on a shaft and co-acting fingers rotatable about a second shaft, for actuating the conveyor and the crusher with an intermittent movement, a pusher for placing the sugar into boxes, and a cam 50 having a plurality of unequal bosses and mounted on the second shaft, the cam actuating the pusher with an intermittent movement.

4. A machine for breaking lump sugar, 55 and for placing it in successive layers, in boxes, comprising, in combination, a conveyor, a crusher, and a pusher, and actuating mechanism for simultaneously operating the three said devices with an intermittent movement, comprising, a first shaft, 60 a drum and a wheel thereon, the conveyor being carried by the drum, a second shaft, a finger wheel thereon, fingers on the finger wheel, a third shaft, a Maltese cross and a 65 drive wheel thereon, the fingers, on rotation of the finger wheel imparting an intermittent movement to the Maltese cross and the drive wheel, the drive wheel directly actuating both the wheel on the first shaft and 70 the crusher, a cam wheel on the second shaft, and a cam arm, connected to the pusher, and bearing against the cam wheel.

In testimony whereof, we have signed our names to this specification.

ALFRED LETORT,
LOUIS CHAMBON.
